DESIGN FOR AN ATOMIZER

Carl W. Sundberg, Birmingham, Mich., assignor
to The De Vilbiss Company, Toledo, Ohio, a cor-
poration of Ohio

Application July 5, 1941, Serial No. 101,915

Term of patent 7 years

To all whom it may concern:

Be it known that I, Carl W. Sundberg, citizen
of the United States, residing at 230 Linden
Street, Birmingham, in the county of Wayne and
State of Michigan, have invented a new, origi-
nal, and ornamental Design for an Atomizer,
of which the following is a specification, refer-
ence being had to the accompanying drawing,
forming part thereof.

In the drawing—

Fig. 1 is a side elevational view of an atomizer
showing my new design; and Fig. 2 is a top plan
view thereof.

The essential feature of my new design resides
in the portions shown in full lines.

I claim:

The ornamental design for an atomizer, sub-
stantially as shown and described.

CARL W. SUNDBERG.
